ELECTRIC IRON THERMOSTAT

Filed Dec. 11, 1946

UNITED STATES PATENT OFFICE

2,537,808

ELECTRIC-IRON THERMOSTAT

Alan Bate, Riverton, Conn., assignor to The Winsted Hardware Manufacturing Company, Winsted, Conn., a corporation of Connecticut

Application December 11, 1946, Serial No. 715,561

2 Claims. (Cl. 219—25)

1

This invention relates to new and useful improvements in thermostatic controls and has particular relation to thermostatic controls forming parts of electrical appliances.

The objects and advantages of the invention will become apparent from a consideration of the following detailed description taken in connection with the accompanying drawing wherein satisfactory embodiments of the invention are shown. However, it is to be understood that the invention is not limited to the details disclosed but includes all such variations and modifications as fall within the spirit of the invention and the scope of the appended claims.

In the drawing:

Fig. 1 is a longitudinal sectional view of an electric iron and showing an application of the invention;

Fig. 2 is a detailed plan view taken as along the plane of the line 2—2 of Fig. 1;

Fig. 3 is a detail elevational view showing the thermostatic control in association with a portion of the sole plate only of the iron of Fig. 1;

Fig. 4 is a view similar to Fig. 3 and showing a modification;

Fig. 5 is a similar view showing a further modification; and

Fig. 6 is a similar view showing yet another modification.

While the control of the invention has other applications, it is herein specifically disclosed in relation to an electric sadiron. Thus, in the drawing, and referring at first more particularly to Figs. 1, 2 and 3, at 10 is generally indicated a sadiron including a sole plate 11 and a shell or casing 12. Against the inner side of the sole plate is an electrical heating device or element 13 maintained against the sole plate as by a filler block 14 but separated from said block by an electrical and heat insulator 15.

Contact prongs or pins 16, adapted for use with any of the usual heater plugs (not shown), are mounted or pass through and are insulated from a rear wall portion 17 of the shell 12. As shown, these prongs are insulated by separators 18 and are clamped to the wall portion 17 between nuts 19 and 20. Any suitable guard device 21 may be arranged about the prongs 16.

At its inner side, the sole plate 11 is provided with a pair of sockets or recesses 22 and 23. A lug 24, having a flared or dove-tailed head portion, has such head portion disposed in the socket or recess 22 and then portions of the sole plate are pinned over against this head portion, as at 25, whereby the lug is made rigid with the sole plate. 55

2

A similar lug 26 has its head portion disposed in the recess 23 and has portions of the sole plate offset or pinned over against it as at 27 whereby such lug 26 is made rigid with the sole plate.

5 A threaded stud 28 extends upwardly from the lug or head 26 and may be integral therewith or may have its inner end threaded into a tapped recess therein. A hollow screw 29 passes through an upper side of the shell or casing 12 and threadedly receives the upper end of the stud 28 whereby the shell 12 is secured to the sole plate. A bracket 30 and a means 31 may be used for securing a handle (not shown) to the shell 12.

An extension 32 of a spring contact arm 33 is 15 fastened to one of the prongs 16 while the other of said prongs is connected with the element 13 as is a spring contact arm 35. The contact arm 33 normally tends to move outwardly or upwardly away from the arm 35 and the latter tends to move downwardly or away from the arm 33. An 20 adjusting screw 36 extends through the upper side of the shell 12 and is adapted to be turned by a handle 37. At its inner end, this screw carries an electrical insulating button or button-like part 38 normally engaging the arm 33 toward the free end of the latter.

Turning of the handle 37 in one direction or the other threads the screw 36 inwardly or outwardly to shift the free end portion of the arm 33 toward the arm 35 or to permit such free end portion of the arm 33 to move away from the arm 35. On its inner or underside, the arm 33 toward its free end carries a contact button 39. Similarly, toward its free end, the arm 35 carries a contact button 40. However, arm 35 extends a substantial distance beyond its button 40 and such extended end portion is normally in engagement with a button 41 of insulating material carried on the upper side of the midportion or substantially the midportion of a metallic element 42, bowed or otherwise upwardly or outwardly offset intermediate its ends.

45 Element 42 is preferably of an alloy of nickel steel, the alloy including 42% nickel. Such material, for my purpose, has advantages in that its coefficient of expansion is constant up to 600° F. or higher. "Invar," a 36 per cent nickel steel, on the other hand, has a very small coefficient of expansion or practically no coefficient of expansion up to approximately 500° F. and then its coefficient of expansion increases very rapidly as the heat increases.

Also, preferably, the element 42 is hardened and flattened, as by rolling, whereby it has a tendency to remain flat. As shown, the element

42 is mounted by being bowed and having its free ends located in notches 43 and 44 in the opposed faces or edges of the lugs 24 and 26. These lugs are so spaced with relation to the length of the element 42 that the latter, in spite of its tendency to assume a flat position, is held in a bowed position between the lugs.

From Figs. 1-3, it will be clear that the bowed element 42 supports the outer end of the arm 35 limiting the extent to which the contact button 40 may move away from the contact button 39. In these figures, the parts are shown positioned with the button 40 engaged with the button 39, or in closed circuit relation therewith, whereby the circuit to the heating element 13 is closed and this situation obtains when the sole plate 11 is below the desired temperature.

It will be understood that the sole plate, at this time being below an ironing temperature, has contracted and contraction of the sole plate resulted in movement of the lugs 24 and 26 toward one another bowing or increasing the degree of curvature of the element 42. The circuit to the heating element being closed, the sole plate will increase in temperature. As this occurs, and the sole plate expands and the lugs 24 and 26 are moved apart or from one another permitting the element 42 to assume a more flattened condition whereby its central portion will be lowered permitting the outer portion of arm 35 to move inwardly separating its contact button 40 from the contact button 39 whereupon the circuit to the element 13 is again opened.

In connection with this operation, it will be understood that the material of the sole plate 11 has a much higher coefficient of expansion than has the material of the element 42. Further, it will be understood that the button 41 working against the extended portion of the arm 35 or that portion beyond the contact 40, a certain leverage is obtained for shifting of the contact 40 into engagement with the contact 39.

As herein shown, the inner ends of the arms 33 and 35 are mounted on the stud 38 but are not in electric engagement therewith. These arms are insulated from the lug 26 and from one another as by means of insulating washers 45 and are clamped in position by a nut 46 threaded down against the washers and arms on the stud 28. A similar nut 47 serves to anchor the extension 32 of arm 33 to one of the prongs 16.

From the foregoing description it will be understood that the prongs 16 being connected with a source of electrical energy, the resistance element 13 will be energized as long as the contact buttons 39 and 40 are engaged. These buttons are permitted to separate only on flattening of the element 42. However, such element is held in bowed condition by the lugs 24 and 26 until the sole plate 11 has expanded a predetermined amount due to the application of heat. The sole plate temperature, at which the button 40 moves away from the button 39, is determined by the position of the latter. Such position is adjustable, being controlled by manipulation of the screw 36 so as to control the position of the button 39 with respect to the button 40 and thus to control the distance the button 40 must move to become engaged with or disengaged from the button 39.

It will be clear that I have an extremely simple arrangement for the purpose intended, the same merely involving the contact button carrying arms 35 and 33 and the bowed element 42. While this element itself is not a bimetallic strip, the

difference in the coefficient of expansion of the material of the sole plate with respect to the material of the element 42 provides for the bowing and flattening of the element.

Fig. 4 shows a slight modification wherein a portion of the sole plate of an iron is designated 50 and has rigid therewith a pair of spaced lugs 51 and 52 fastened thereto in the manner previously described with respect to the lugs 24 and 26. Lug 51 carries a short threaded stud 53 while the lug 52 carries a longer threaded stud 54 which is the same as the stud 28 previously described. In this figure, the arms 33 and 35 are again employed and they are provided with the contact buttons 39 and 40.

The essential difference between the structure of Fig. 4 and that of Figs. 1-3 resides in the fact that in the modification an element 55 has perforated ends disposed over the studs 53 and 54. This element is thus anchored to the studs and a nut 56 retains the element or stud 53 while the nut 46 above described accomplishes the same purpose for that end of the element on the stud 54. Element 55 is of the material of the element 42 and while the element has a normal tendency to assume a flat condition, it is held in bowed condition by being anchored on the studs 53 and 54. Intermediate its ends this element carries an insulating button 57 corresponding with and for the purpose of the button 41 previously described.

With this construction, it will be clear that as the sole plate 50 is heated and expands, the studs 53 and 54 will be moved in directions away from one another permitting the bowed or offset element 55 to flatten somewhat. In fact, as the studs are thus moved outwardly and pull the ends of element 55 apart, the latter is flattened, somewhat, regardless of whether it has a normal tendency to seek a flat condition. This permits the arm 35 to move downwardly carrying its contact button 40 away from the contact button 39 of the arm 33. On the sole plate cooling, it contracts shifting the studs 53 and 54 back toward one another and causing a higher degree of curvature in the element 55 whereby the arm 35 will be flexed upwardly to engage its contact button 40 with the contact button 39 again closing a circuit through the resistance element 13.

Referring now to the modification of Fig. 5, where the parts there are the same as previously described, they have been given the same reference numbers. In this construction, the lugs 51 and 52 are again made fast to the sole plate 50 but the arm 35 and its contact button 40 are omitted, although the arm 33 and its contact button 39 are employed. Now, the bowed or offset element 55 carries a contact button 60 adapted to come into circuit closing relation with the contact button 39. To this end, a lead or extension 61 from the element 55 is connected in the circuit of the resistance element 13. For this type of construction, the anchored ends of the element 55 are insulated from the lugs 51 and 52 and the studs 53 and 54 by suitable dielectric constructions 62.

In the modification, the contact button 60 is shown engaged with the contact button 39 and therefore it will be understood that the sole plate 50 is below ironing temperature. At this time, the element 55 is in bowed condition as its end portions move inwardly with the studs 53 and 54 on cooling of the sole plate.

Now, as the sole plate heats and expands, the studs 53 and 54 will be shifted from one another

and will permit of flattening of the element 55 whereby its button 60 will be carried from engagement with the button 39 opening the circuit through the resistance heating element 13. In the particular construction of Fig. 5, it is noted that a minimum of elements are used and yet a fully operative device for the intended purpose has been provided.

In Fig. 6, the construction is somewhat similar to that in Figs. 1-3 with the exception that the lug or head 24 is entirely omitted. In this figure many parts are the same as those in Figs. 1-3 and have been given the same reference numbers. The modification consists essentially in that a bowed or offset element 70 of high content nickel steel (of the material of the element 42) has flattened end portions 71 and 72 which are welded or in any other similar manner made rigid with the inner side of the sole plate 11.

Element 70 includes an insulating button 73 engaging the underside of the arm 35 inwardly of the free end thereof. With this construction, it will be clear that as the sole plate 11 expands, the ends of element 70 are drawn apart and the latter thus becomes somewhat flattened and permits the arm 35 to move downwardly carrying its contact button 49 away from the contact button 39 of the arm 33 and thus opening the circuit of the heating element 13.

On cooling of the sole plate 11, the anchored ends 71 and 72 of element 70 will be carried toward one another as the sole plate contracts and thus additional bow imparted to the element 70 whereby its insulating button 73 pushing upwardly on the arm 35 will bring the contact button 49 into engagement with the contact button 39 to again close the circuit to the element 13. This is the condition of the parts as seen in Fig. 6.

In this construction, due to the fact that the button 73 engages the arm 35 between the anchored end of the latter and the contact button 49, there is a difference in the leverage over that of the constructions of Figs. 1-4. However, the difference is not of material importance. In Fig. 6 the head or lug 26 and its stud 28 have no part in the mounting of the element 70 but they do serve the other purposes illustrated in Fig. 1.

In the various modifications shown the bowed element, when in a flat condition, is of greater length than the distance which may separate its ends under any useful expansion of the sole plate. For example, with the construction of Figs. 1-3, the lugs 24 and 26 never move apart sufficient to permit of the element 42 assuming a flat condition. There is always some compression of the element so that it constantly is bowed upwardly to some extent whereby on contraction of the sole plate it is further bowed upwardly. It is never permitted to assume a condition where contraction of the sole plate might result in bowing of the element downwardly. Further, since it is always under some compression, it will not drop out of place in the assembly.

In the constructions of Figs. 4 and 5, where the ends of the element 55 are disposed over the studs 53 and 54, the distance along the element when flat, between the perforations in the element for the accommodation of said studs, is greater than the distance between the studs in a highly expanded condition of the sole plate and even under a condition where the plate would be too hot for use in ironing. Clearly, the

same condition prevails with the construction of Fig. 6.

Thus, it will be understood that in all the figures, the bowed element is of such length and is so anchored and constructed that it never assumes an actual flat condition, the operation of the switch involving merely a variation of the degree of curvature of the element as it moves toward a flat condition on expansion of the sole plate and as its degree of curvature is increased on cooling of the sole plate.

From the foregoing description it will be clear that in each of the several forms herein disclosed, the bowed or offset element has its ends anchored to the sole plate. Thus, in Figs. 1-5 the element is anchored to the sole plate through the instrumentality of the lugs and studs. In Fig. 6, the element is anchored to the sole plate by welding, soldering, or the like. Due to the difference in the coefficient of expansion of the bowed or offset element and the sole plate, these two parts together form a bimetallic construction controlling opening and closing of the switch for the circuit of the heater 13.

Where in the description and in the following claims the element variously numbered 42, 55 and 70 is described as "bowed" it will be understood that the same is not necessarily a true arc. The word "bowed" as used herein is intended to cover any offset or bulged structure which tends to flatten as the plate or plate-like portion expands on heating and tends to bow or bulge or otherwise increase in height when such plate or plate-like portion contracts as it suffers a drop in temperature. Thus, for example, the structures 42, 55 and 70 may have angular bends and for the purpose of the present disclosure and the appended claims be "bowed."

Having thus set forth the nature of my invention, what I claim is:

1. In a sadiron, a sole plate, an electrical heating element overlying said sole plate for heating said sole plate, said heating element having a gap therein exposing an area of the top of said sole plate at about the mid-portion thereof, a pair of positioning elements secured to said sole plate and spaced apart lengthwise thereof, each positioning element having clamping means, said positioning elements being located wholly within said gap in spaced relation to said heating element, an upwardly bowed strip member securely fastened at its opposite ends to said positioning elements by said clamping means and disposed wholly within the area defined by said gap and spaced from said heating element, said strip member consisting of a nickel-iron alloy having a substantially uniform thermal coefficient of expansion throughout a range of temperatures up to at least 600° F., said coefficient of expansion being less than that of the sole plate, and switch means for opening and closing a circuit to said heating element, said switch means being controlled by said bowed member to open and close in response to increase and decrease of the temperature of said sole plate.

2. In a sadiron, a sole plate, an electrical heating element for heating said sole plate, said heating element having a gap therein exposing an area of the top of said sole plate at about the mid-portion thereof, a pair of threaded studs secured to said sole plate and spaced apart lengthwise thereof, said studs being located wholly within said gap in spaced relation to said heating element, an upwardly bowed strip member having apertures in its opposite ends receiving said studs,

and threaded members to securely fasten said strip member and studs together, said strip member being disposed wholly within the area defined by said gap and spaced from said heating element, said strip member consisting of a nickel-iron alloy having a substantially uniform thermal coefficient of expansion throughout a range of temperatures up to at least 600° F., said coefficient of expansion being less than that of the sole plate, a pair of relatively movable, normally spaced apart switch contacts carried by one of said studs and insulated therefrom, means connecting said contacts in a circuit with said heating element, and insulating means mounted at the mid-portion of said strip member and bearing against one of said switch contacts to engage and disengage said contacts in response to variation in the temperature of said sole plate.
